RUMBLE SEAT PROTECTOR

Samuel I. Goldberg, Brooklyn, N. Y.

Application April 25, 1933, Serial No. 667,923

1 Claim. (CL 296—99)

This invention relates to protective coverings and is particularly applicable as protection to persons in a rumble seat of an automobile, the improved structure being for that reason called 5 a rummbrella.

An object of the invention is the provision of a structure of the character mentioned which may be readily set up and taken down.

Another object of the invention is the provision of a structure of the character mentioned 10 which is adjustable to automobiles of different sizes.

Other objects will be appreciated from a reading of the following specification.

15 The invention will be fully and comprehensively understood from a consideration of the following detailed description when read in connection with the accompanying drawing which forms part of the application, with the understanding, however, that the improvement is capable 20 of extended application and is not confined to the exact showing of the drawing nor to the precise construction described and, therefore, such changes and modifications may be made 25 therein as do not affect the spirit of the invention nor exceed the scope thereof as expressed in the appended claim.

In the drawing:

Fig. 1 is a bottom plan view of the structure 30 of my invention in open position.

Fig. 2 is an elevational view of the structure in closed or protecting position over the rumble seat of an automobile; and

Fig. 3 is a detail view showing one means of 35 supporting the device.

Referring to the drawing for a more detailed description thereof, the structure comprises a square top 5, to the sides edges of which are secured side walls 6 and 7 and to the rear edge 40 of which is secured a back wall 8. Said top, side walls and back wall are preferably of flexible water-proof material. The structure or article is supported on a standard 9 which is attached to a part 10 of the automobile by passing 45 thru the vertical portion 11 of the T-shaped member 12 and held therein by means of a thumb screw 13. A right angular member 14 has a horizontal portion 14a extending into the horizontal portion 12a of the T-shaped member 50 12 and is adjustably held therein by means of a thumb screw 15. The vertical portion 14b of the right angular member 14 is hollow and receives a pin 16 which is connected to the member 10 of the automobile. There is an annular groove 55 16a formed on the periphery of the pin 16 and

the inner end of a thumb screw 16b fits into this groove and presses against the mentioned pin, the thumb screw 16b passing thru the wall of the vertical portion 14b of the member 14 and threadedly engaging the wall. In the rummbrella 5 of my invention, the thumb screw 16b may be slightly loosened and the connected members 12 and 14 swung into a position entirely under the member 10 of the car.

Said top 5 is supported by stays 17 which are 10 connected to the standard 9 in the same manner as the stays of an umbrella, whereby the top may be readily opened and closed. The ends of the back wall 8 are secured to rigid reinforcing strips or bars 8a and the front ends of the side 15 walls 6 and 7 are secured to rigid reinforcing bars or strips 6a and 7a, respectively. The sides 6 and 7 and the back wall 8 have windows 6b, 7b and 8b, respectively. Means are provided for joining the rear ends of the side walls with the 20 respective adjacent ends of the rear wall, said means being shown as consisting of slide fasteners 18 of the Zipper type, it being understood that the adjacent edges of the rear and side walls are joined when the structure is in 25 closed position, as shown in Fig. 2. Straps 19 are secured to the forward ends of the side walls in order to tie the side and rear walls around the top when the latter is in closed or collapsed position, but primarily to be tied to the standard 30 9 and thereby securely anchor the side walls 6 and 7.

Elastic loops 20 are secured to the bottoms of the side and rear walls so that when the structure is closed said walls may be held in positions wrapped around the closed top by placing the loops around that part of the standard 9 which projects above the top. The structure described, when in closed position, may be conveniently and neatly carried in a casing made 35 for the purpose. It will readily be seen from Fig. 2 that the structure described provides a protective covering for the person or persons occupying the rumble seat of the automobile, the latter being designated by the numeral 21 and 40 45 the back of the rumble seat by the numeral 22.

What is claimed is:

In combination with an automobile having a rumble seat, a cover ledge in front of said seat and a closed body in front of said ledge, an um- 50 brella structure including a standard and provided with a rear curtain, and with side curtains which overlap the top and sides of said body, a bracket comprising a first end part fixed to the lower face of said ledge, an intermediate part, 55

means for securing said intermediate part to said first end part, a second end part secured to said intermediate part for forward and rearward adjustment and extending rearwardly of said ledge, said second end part holding said standard and the latter being vertically adjustable there-

in, said intermediate part and second end part being adapted to be swung under said ledge when said standard is removed from said second end part and said means connecting said intermediate and first end part is loosened.

SAMUEL I. GOLDBERG.
